UNITED STATES PATENT OFFICE.

JOHN MAXWELL, OF ONEIDA, NEW YORK.

DESIGN FOR A CASKET-LID.

SPECIFICATION forming part of Design No. 17,108, dated February 8, 1887.

Application filed December 27, 1886. Serial No. 222,675. Term of patent 14 years.

To all whom it may concern:

Be it known that I, JOHN MAXWELL, of Oneida, in the county of Madison, in the State of New York, have invented and produced a new and original Design for Burial-Casket Lids, of which the following, taken in connection with the accompanying drawings, is a full, clear, and exact description.

This design has more particular reference to the form of the lids of metallic caskets, especially the foot-section thereof, and is fully illustrated in the annexed drawings, wherein—

Figure 1 is a perspective view of a burial-casket lid embodying my design. Fig. 2 is a central longitudinal section of the same; and Fig. 3 is a transverse section on line xx , Fig. 1.

A represents the head-section of the lid, and B the foot-section of the same. This foot-section has a flat longitudinal central portion, a , raised above the margin of the lid and extending in one uniform plane, and tapering from the junction of the head-section A and foot-section B part way toward the foot of the lid, and of triangular form, with the base of the triangle at the aforesaid junction of the sections A B. A sloping portion, b , is extended along the sides and around the foot or apex of

the raised central portion, and vertical or approximately vertical portions or strips c , joining the side edges of the central portion, a , with the sloping portion b and tapering toward the foot of the lid, as shown in Figs. 1 and 2 of the drawings.

What I claim is—

In a design for a burial-casket lid, a flat central portion raised above the marginal portion of the lid and extending in one uniform plane, and tapering from the junction of the head-section and foot-section part way toward the foot of the lid, a sloping portion along the sides and around the foot of the raised central portion, and vertical or approximately vertical strips joining the side edges of the central portion with the sloping portion, substantially as described and shown. 35

In testimony whereof I have hereunto signed my name and affixed my seal, in the presence of two attesting witnesses, at Syracuse, in the county of Onondaga, in the State of New York, this 18th day of December, 1886.

JOHN MAXWELL. [I. S.]
